**LAMP FOR AUTOMOBILE DASHBOARDS,
PANELS, AND THE LIKE**

Alan William Ronald Podmore, Dartford, Kent, England,
assignor to AMP Incorporated, Harrisburg, Pa.

Filed Aug. 26, 1963, Ser. No. 76,381

Term of patent 14 years

(Cl. D48—20)

FIGURE 1 is a perspective view of a lamp for automobile dashboards, panels, and the like from above showing one front and one side;

FIGURE 2 is a front elevation thereof;

FIGURE 3 is a side elevation thereof;

FIGURE 4 is a top plan view thereof; and

FIGURE 5 is a bottom plan view thereof.

I claim:

The ornamental design for a lamp for automobile dashboards, panels, and the like substantially as shown.
